[57] CLAIM

The ornamental design for a bottle for perfume, toilet water or the like, as shown.

DESCRIPTION

FIG. 1 is a front elevational view of a bottle for perfume, toilet water or the like showing my new design, all four sides being identical;

FIG. 2 is a top plan view thereof;

FIG. 3 is a bottom plan view thereof.
The rear elevation and the right and left side elevation views are mirror images of the front elevational view.

FIG. 1

FIG. 2

FIG. 3
